UNITED STATES PATENT OFFICE

LOUIS W. REINHARDT, OF BROCKTON, MASSACHUSETTS, ASSIGNOR TO GEORGE E. BELCHER COMPANY, OF STOUGHTON, MASSACHUSETTS, A CORPORATION OF MASSACHUSETTS

SPRING-LINK LAST

Application filed September 21, 1929. Serial No. 394,282.

My present invention relates to certain improvements in two part lasts. In its general construction and operation it embodies the principles of Letters Patent to Otto A. Peterson, No. 1,195,266, patented August 22, 1916. In that last a resilient connecting link is used which in the form shown is a flat unitary member in practice made as a forging and having just enough resiliency to provide for the snapping by action characteristic of that last, so that the parts are held in either broken or extended position.

While my present invention contemplates a last working on the same principle, it provides for certain novel features in the construction of the resilient link as will be more fully set forth in the specification which follows and as illustrated in the accompanying drawings. In these drawings a characteristic example of my link is shown as follows:

Fig. 1 is a side view of a last in accordance with my invention.

Fig. 2 a view of the last collapsed and partly broken away to expose the link.

Fig. 3 a side view of the link member.

Fig. 4 an end view.

Fig. 5 a section on the line 5—5, of Fig. 3 and

Fig. 6 a bottom edge view of the link.

In the drawings the fore part of the last is indicated at 1 and the heel part at 2. The fore part 1 has a convex knuckle 10 and the rear part a concave member 12. The last is provided with the usual jack or last pin receiving socket 3. The resilient link member generally indicated at 4 is formed of sheet metal and comprises two leaves or folds 4¹ connected by a U-shaped fold or bend 4² disposed longitudinally of the link and the last when it is assembled in a last and transversely to the axis of the knuckle 10 on which the heel part turns.

The side plates 4¹ are notched as at 5 so as to form terminal arms 6 which correspond generally with the arms of the U-shaped link of the Peterson patent above referred to. These extensions 6 are provided with pin holes and bearings 7 to receive the pins 8 which pivotally fasten the links to the fore part and heel part as in said Peterson patent.

The notch 5 is made of sufficient length to leave a rather narrow arched portion at the center of the last which provides just sufficient resiliency to permit the snapping by action characteristic of this type of last. The spacing of the side plates 4¹ of the extension 6 gives a somewhat wider bearing on the pins 8 and these parts are accommodated in recesses 9 in the fore part and heel part of somewhat greater width than the slots in the original Peterson construction.

In order to reenforce the spaced sides 6 and to maintain the outer edges in spaced relation any suitable bridging or reenforcing means may be used, if desired. As shown the outer corners 6' are bent inward so as to form stops to limit relative inward movement of the side 6 if subjected to pressure.

My link is capable of simple and inexpensive manufacture from sheet stock which can be struck out and bent and sufficiently hardened and tempered to give it the desired strength and resiliency. In assembly the pins 8 are driven so as to slightly tension the link which thus holds the fore part and heel part together with the knuckle members 10 and 12 contacting and thus take up any wear that may occur between these parts. My links also provide great lateral strength insupporting and guiding the last parts and makes possible a very neat and compact last structure and assembly. While the form shown is a preferred form it is capable of some variation in design and may be made of other stock than sheet metal, although that material is indicated as preferred.

What I therefore claim and desire to secure by Letters Patent is:

1. In a two part last comprising a fore part and a heel part having cooperating pivot bearings, a resilient link pinned to the fore part and heel part at points which are in a line on one side of the pivot when the last is extended and on the other side when the last is collapsed, said link comprising a sheet metal member folded on a line longitudinally of the last and having a central cut out portion.

2. In a two part last comprising a fore part and a heel part arranged for relative move-

ment about a common pivot, a connecting member comprising a pair of spaced plates integrally connected at one edge by a portion arched about an axis transverse of the axis of movement of the last parts, said connecting member being connected to the two last parts at points which are on one side of the axis of movement of the last parts when in extended position, and at the other side of said axis when the last is collapsed.

10 3. In a two part last comprising a fore part and a heel part arranged for relative movement about a common axis, an integral resilient connecting member comprising a pair of vertically disposed spaced plates connected at one edge by a portion arched about an axis transverse of the axis of movement of the last parts said plates being notched at their central portion to leave the arched portion as a resilient web the ends of said member being connected to the two last parts at points which are on one side of the axis of movement of the last parts when in extended position and at the other side of said axis when the last is collapsed.

15 4. A resilient link for a two part last comprising a member of U-shaped cross section having a relatively narrow central portion and extended end portions provided adjacent to their terminals with pin bearings.

20 5. A connecting link for a two part last comprising a member of U-shaped cross section including spaced sides provided adjacent to their ends with openings to receive pins to pivotally connect the member with the respective last parts, said sides being of sufficiently narrow width medially to provide for slight transverse resiliency of the member in a direction at right angles to the axis of said

25 6. A connecting link for a two part last comprising a member composed of spaced side portions connected with one another and provided adjacent to their ends with openings to receive pins to pivotally connect the member with the respective last parts, said sides being of reduced width medially to provide for slight transverse resiliency of the member in a direction at right angles to the axes of said

30 7. A connecting link for a two part last comprising a member of U-shaped cross section including spaced sides provided adjacent to their ends with openings to receive pins to pivotally connect the member with the respective last parts, said sides being of sufficiently narrow width medially to provide for slight transverse resiliency of the member in a direction at right angles to the axes of said

35 8. A connecting link for a two part last comprising a member of U-shaped cross section including spaced sides provided adjacent to their ends with openings to receive pins to pivotally connect the member with the respective last parts, said sides being of sufficiently narrow width medially to provide for slight transverse resiliency of the member in a direction at right angles to the axes of said

to their ends with openings to receive pins to pivotally connect the member with the respective last parts, said sides being of sufficiently narrow width medially to provide for slight transverse resiliency to the member in a direction at right angles to the axes of said openings, free edge portions of the sides of said member being bent inwardly to provide stop formations to limit inward movement of said sides relative to one another.

In testimony whereof I affix my signature.

LOUIS W. REINHARDT.
